UNITED STATES PATENT OFFICE.

JAMES D. WILSON, OF ST. LOUIS, MISSOURI.

DESIGN FOR A FLUSHING-TANK.

SPECIFICATION forming part of Design No. 27,696, dated September 28, 1897.

Application filed December 26, 1896. Serial No. 617,106. Term of patent 14 years.

To all whom it may concern:

Be it known that I, JAMES D. WILSON, a citizen of the United States, residing at St. Louis, in the State of Missouri, have invented and 5 produced a new and original Design for Flushing-Tanks, of which the following is a specification, reference being had to the accompanying drawings, by which it is shown.

Figure 1 is a front elevation of a flushing-10 tank and wall-plate embodying my design; Fig. 2, a side elevation of the same; and Fig. 3 is an isometric view, these three views being deemed necessary to fully illustrate my 15 design.

My design consists in the shape of the front 20 of the tank, which curves downwardly and backwardly from near the top to the bottom, in connection with the form of the ends of the tank and the form and arrangement of the 25 molding and wall-plate.

Referring to the drawings, A is the curved 25 front of the tank. When I speak of this curvature, I wish to be understood as referring to the curve of its body, and the molding is not included in that curve, which terminates a short distance below the molding.

B denotes the bottom of the tank, which is flat and substantially horizontal from the

point a, where the curve of the front of the tank merges into it.

The letters b b' indicate pipe connections forming no part of my design.

C denotes the ends of the tank, which are flat, and their front edges c are curved and shaped to correspond with the shape and 35 curvature of the front and bottom of the tank.

D denotes the wall-plate or pipe-board, extending down from the back of the tank and having its sides d curved inwardly toward the central portion d', giving to the plate a 40 form that harmonizes well with that of the body of the tank.

Extending around the upper edges of the front and ends of the tank is a molding E, that inclines or flares outwardly and upwardly and 45 that has a beading at its lower edge.

My invention relates only to the exterior form of the tank. The form or shape of the interior is immaterial.

What I claim, and desire to secure, is— 50

The design for a flushing-tank, substantially as shown and described.

JAMES D. WILSON.
